COMBINED BOTTLE AND CLOSURE THEREFOR

Richard John Waddington, Amersham, Peter Colin Webb, Sacombe Green, near Ware, and Ralph N. Ashworth, Walton-on-Thames, England, assignors to Imperial Chemical Industries Limited, London, England, a corporation of Great Britain

Filed Oct. 27, 1967, Ser. No. 9,188

Claims priority, application Great Britain Apr. 28, 1967

Term of patent 14 years

Int. Cl. D9—01

U.S. Cl. D9—66

We claim:

The ornamental design for a combined bottle and closure therefor, as shown.
